UNITED STATES PATENT OFFICE.

RICHARD C. NUGENT, OF CINCINNATI, OHIO.

FRICITION-CLUTCH.

No. 841,564.

Specification of Letters Patent.

Patented Jan. 15, 1907.

Application filed August 28, 1906. Serial No. 382,367.

To all whom it may concern:

Be it known that I, RICHARD C. NUGENT, a citizen of the United States, residing at Cincinnati, in the county of Hamilton and State of Ohio, have invented certain new and useful Improvements in Friction-Clutches, of which the following is a specification, reference being had therein to the accompanying drawings.

10 The invention relates to a friction-clutch, and more particularly to clutches having an expansible element for frictional engagement with a rotatable element to positively impart movement to the latter.

15 The primary object of the invention is the provision of a driving member having an expansible element when actuated to frictionally engage a revoluble element to impart corresponding movement thereto.

20 Another object of the invention is the provision of a tension-controlled means for holding the expansible element in a locked position.

25 A further object of the invention is the provision of means for actuating the locking member to hold the same in an operative position and for release thereof.

30 A still further object of the invention is the provision of a rotary driving element and a rotatable shell element for receiving the same and an intermediate expansible member when actuated for locking the rotatable shell element to the driving element for corresponding movement therewith.

35 Other objects of the invention is the provision of means simple in construction, efficient, durable, and inexpensive in the manufacture.

40 With these and other objects in view the invention consists in the construction, combination, and arrangement of parts, as will be hereinafter described, and as illustrated in the accompanying drawings, which disclose the preferred embodiment of the invention.

45 However, it is to be understood that changes, variations, and modifications may be made that come properly within the scope of the claims hereunto appended without departing from the spirit of the invention.

50 In the drawings, Figure 1 is a perspective elevation of the friction-clutch. Fig. 2 is a sectional view thereof. Fig. 3 is a transverse sectional view. Fig. 4 is a perspective elevation of the expansible member in detail and being detached from the friction-clutch.

55 Similar reference characters indicate cor-

responding parts throughout the several views.

In the drawings the numeral 2 designates a rotatable shaft having fixed thereto a disk 3, the latter having a radial bore 4, terminating at one extremity in a cut-out portion 5 at the periphery of the said disk 3 and at the other end in an opening 6, contiguous with the circumference of the shaft 2, and for receiving a pin 7, having at one end a wedge element 8, the latter adapted to have its seat in the cut-out portion 5 of the disk 3. The other end of the pin 7 has an enlargement 9, resting in a keyway 10, cut in the shaft 2 and extending longitudinally a distance therein. Surrounding the pin 7 is a spiral tension-spring 11, having one terminal bearing against a shoulder 12 on the enlarged terminal 9 of said pin 7 and the other end having its bearing against a detachable collar 13, the same being screw-threaded and engaging screw-threads in the wall of the bore 4, the upper face of the collar 13 when screwed into the wall of the bore 4 being flush with the base-face of the cut-out portion 5 in the disk 3, and said collar surrounds the pin 7, holding the same in position within the bore 4 in the disk 3.

Surrounding the disk 3 at the periphery thereof is an expansible split ring 13, the latter held against rotary movement with the disk 3 by a block 14, carried by the disk 3 at a distance from the cut-out portion 5 of said disk, one terminal of the said expansible ring 13 abutting against the said block 14, the other terminal of the ring 13 having secured thereto a block 15, having its seat in the cut-out portion 5 of the disk 3 and provided with an inclined surface 16, contiguous with the inclined face 17 of the wedge element 8.

Loosely mounted and revoluble on the shaft 2 is a shell-pulley 18, the same adapted to house the disk 3 and the expansible ring 13, said pulley 18 being held against longitudinal displacement by a collar 19, fixed to the shaft by a set-screw member 20. On the shaft 2 is a slideable sleeve 21, having fixed thereto key 22 at opposite sides thereof, the same provided with inclined ends 23 and adapted to slide in the keyway 10 in the shaft 2. The keys 22 when shifted with the sleeve 21 in the keyway 10 and in one direction bring the inclined end 23 into contact with the enlarged portion 9 of the pin 7, causing the same to be raised in the bore 4 in opposition to the tension-spring 11 and through the

medium of the said pin will move the wedge element 8 radially with respect to the shaft 2, and the inclined face 17 of the said element will engage the inclined face 16 of the block 15, 5 carried by the expansible ring 13, causing the latter to yield and frictionally engage the interior of the shell-pulley 18, thereby locking the latter, so as to cause movement thereof with respect to the movement of the disk 3, 10 driven by the shaft 2. When it is desired to free the shell-pulley 18, it is necessary to shift the sleeve 21 in an opposite direction on the shaft 2, which will carry the key 22 therewith, returning the same from beneath the 15 enlarged portion 9 of the pin 7, and the tension-spring 11 will automatically return the wedge element 8 to its seat in the cut-out portion 5 of the disk 3, thus decreasing the expansion of the ring 13, whereby the latter will 20 be relieved from frictional contact with the interior face of the shell-pulley 18, which will be freed from relative movement with respect to the said disk 3.

It will be apparent that the sleeve 21 can 25 be actuated by any well-known shifting device, so as to move the same longitudinally in opposite directions on the shaft 2 to actuate the expansible ring 13, positioned intermediate the said disk 3, and the shell-pulley 18, 30 forming the friction-clutch. Furthermore, when the wedge element 8 is moved outwardly from its seat, formed by the cut-out portion 5 in the disk 3, causes the inclined face 17 of said wedge element to contact 35 with the inclined face 16 of the block 15, carried by the expansible ring 13, to circumferentially move at the periphery of the disk 3, and the other terminal of said ring will abut against the block 14, thus limiting the movement of the said ring and causing the same 40 to frictionally contact with the shell-pulley 18, thus locking the disk and pulley together.

Having described the invention, what is claimed is—

45 1. In a friction-clutch, a rotatable shaft having a disk fixed thereto provided with a radial bore, a pin mounted in said bore, one terminal thereof having an enlarged portion, a wedge element carried at the other terminal 50 of the pin and having an inclined face, a split expansible ring mounted at the periphery of

the disk, a block carried by the ring and having an inclined surface for contact with the inclined face of the wedge element, a block fixed to the disk at the periphery thereof for forming an abutment for one terminal of the split ring, a shell-pulley surrounding the disk and the expansible ring for frictional engagement with the latter, a sleeve slidable on the shaft and having a key, said shaft provided 55 with a key-guide for receiving the key, and means for moving the sleeve to bring the key into engagement with the enlarged portion of the pin for actuating the wedge element to impart movement to the expansion- 60 ring for frictional engagement with the shell-pulley to lock the same with the disk and cause corresponding movement therewith.

2. In a clutch, the combination with a shaft and a disk rigid thereon, of a spring-retracted pin radially mounted in the disk, a wedge-segment carried by the outer end of said pin abutting against a shoulder on the disk, an expansible ring mounted circumferentially on the disk, an abutment carried by 70 the disk for engagement by the end of the expansible ring, a wedge carried by the opposite end of the ring to co-operate with the radial wedge, a shell-pulley inclosing the expansible ring, and a key to engage the inner end of the 75 radial pin to force the same outward and cause expansion of the ring.

3. The combination with a shaft and a rigid disk thereon, a pin radially movable in the disk, a wedge element on the outer end of the pin engaged in a recessed portion in the periphery of the disk, of an expansible ring 85 encircling the disk having one of its ends engaging an abutment on the disk, a wedge element carried by the opposite end of the said 90 ring adapted to be engaged by the radial wedge, a shell-pulley rotatively inclosing the disk and expansible ring, a slidable key to engage the radial pin to force the wedge radially outward.

In testimony whereof I affix my signature in presence of two witnesses.

RICHARD C. NUGENT.
